Primary Examiner — Rashida C. Walshon

(57) CLAIM

The ornamental design for a set of socks with packaging, as shown and described.

DESCRIPTION

The patent or application file contains at least one drawing executed in color. Copies of this patent or patent application publication with color drawing(s) will be provided by the Office upon request and payment of the necessary fee.

Fig. 3.1 is a three-quarters view of a first sock, showing my new design.

Fig. 3.2 is a three-quarters view of a second sock, showing my new design.

Fig. 3.3 is a three-quarters view of a box for holding socks, showing my new design.

Fig. 3.4 is a three quarters view of a packaging cup for holding rolled socks, showing my new design.
